UNITED STATES PATENT OFFICE.

BENJAMIN W. GRIST, OF READING, PENNSYLVANIA.

HOISTING-DRUM FOR ELEVATORS.

SPECIFICATION forming part of Letters Patent No. 328,934, dated October 27, 1885.

Application filed September 17, 1885. Serial No. 177,331. (No model.)

To all whom it may concern:

Be it known that I, B. W. GRIST, a citizen of the United States, residing at Reading, in the county of Berks and State of Pennsylvania, have invented certain new and useful Improvements in Hoisting-Drums for Elevators; and I do hereby declare the following to be a full, clear, and exact description of the invention, such as will enable others skilled in the art to which it appertains to make and use the same.

In the operating of elevators of various descriptions much difficulty has been experienced in procuring reliable machinery for effecting the raising and lowering of the load with safety; and to this end many devices have been devised which have been complicated in their construction, and in many instances wholly unreliable in their operation.

20 The object of my invention is to produce a simple, safe, durable, and reliable means for engaging and disengaging a hoisting-drum with and from a power-shaft, and to transfer the power of the driven shaft to a drum loosely mounted thereon.

The invention consists in the constructions hereinafter described, and particularly pointed out in the claims.

In the accompanying drawings, which form 30 a part of this specification, Figure 1 represents a vertical longitudinal section of a hoisting-drum and friction-gear mounted upon a shaft attached to the connecting-rod of an engine. Fig. 2 is an end view of the pedestal, 35 showing the internal gear formed upon its flange and the gear-wheels which engage therewith. Fig. 3 is a side view, partly in section, of the friction-disk and its gear-wheels secured thereto. Fig. 4 is an end view looking to 40 ward the engine from the line *xx*.

Reference being had to the drawings and the letters of reference marked thereon, A represents a steam-engine with its connecting-rod B attached to a crank, C, for converting 45 the linear motion of the piston into rotary motion and imparting it to the shaft D.

Upon the shaft D is loosely mounted a drum, E, which is provided at one end with a disk bearing conical friction-surface F, and at the 50 other end with a head, G, having a groove, *a*, formed in its circumference.

H represents a friction-disk loosely mounted on shaft D, and having a conical bearing-surface, I, formed upon it which corresponds with the angle of the surface F formed upon the 55 disk of the drum. The disk H is provided with two shafts, *b b*, which are secured thereto, and upon which revolve two gear-wheels, *c c*, which engage with a corresponding gear-wheel, *d*, fixed upon the driving-shaft D, and with 60 gear-teeth formed upon the inner surface of the flange K, formed upon the disk L of the pedestal M, which supports the outer end of the shaft D, the opposite end being supported in a bearing, M', secured to the engine-frame, 65 as shown in Fig. 1. It will be observed that the gear-wheels *c c* and *d* are of the same diameter, and that the latter revolves in a direction opposite to that of the former, as indicated by arrows, as shown in Fig. 2. The 70 diameter of the wheels *c c* and *d* may, however, be varied, as circumstances may require.

Around the hub *n* of the drum is formed a groove, *e*, in which is secured a yoke, *f*, and to which is connected a lever, O, fulcrumed 75 at *g* to an arm, P, projecting out from the engine-frame.

In the groove *a*, formed in the head G, is placed a band, *h*, one end of which is secured to a lever, *i*, and the other end at *j* to a foot-lever, R, fulcrumed at *k*, the object of which is to form a brake to arrest the motion of the revolving drum during the descent of the elevator car or bucket, and thereby control its speed, or after it has been disengaged from 85 the friction-disk H, or to hold the drum in a fixed position when the engine is running and it is not desired to use its power for hoisting purposes.

The construction of the various parts of the 90 machinery having been described in detail, the operation is as follows: The engine being in motion and the shaft D revolving, carrying with it the gear-wheel *d*, when the operator desires to use the hoisting-machinery he seizes 95 the lever O and moves the drum E upon the shaft, bringing the friction-surface F on the drum into contact with the corresponding surface, I, of the disk H, which will securely lock the drum and the disk together. The power 100 of the engine imparted to the shaft D is now transmitted to the drum through the medium

of the gear-wheel *d*, which is secured to the shaft and revolves with it and the gear-wheels *c c*, which engage with the wheel *d* and with the gear-teeth formed on the inner surface of the flange *K*, which is a fixed part of the pedestal *M*. The power thus imparted by the shaft causes the gear-wheel *d* to turn in one direction, and the wheels *c c*, meshing with it and the fixed gear in the flange *K*, to revolve 10 in the opposite direction, while the disk *H* and the drum are locked together by frictional contact and are made to revolve with the shaft *D*. To release the drum, it is moved away from contact with the disk *H*, when it will 15 again assume its normal condition.

The operation of the brake is obvious. The attendant, by pressing his foot upon the lever *R*, causes the band *h* to be tightened around the circumference of the head *G*, and thus 20 produce friction between the band and the surface of the head, upon which it bears.

By my invention I have greatly simplified the construction of the parts forming the friction-gear as compared with similar devices 25 which have preceded it, and in which two sets of gear-wheels are employed for imparting the power of the shaft to the drum.

Having thus fully described my invention, what I claim is—

30 1. The combination of a power-driven shaft, a gear-wheel fixed thereon, a friction-disk loosely mounted on said shaft and carrying two gear-wheels, a fixed annular gear, and a friction-surface adapted to be brought into 35 contact with the disk, substantially as described.

2. A power-shaft having loosely mounted thereon a drum and a friction-disk, and a gear-wheel fixed to the shaft and revolving therewith, in combination with two gear-wheels 40

revolving upon axles secured in the loose disk, and a stationary gear, substantially as described.

3. A pedestal forming a bearing for a shaft and provided with a disk having a flange, upon the inner surface of which gear is formed, in combination with a drum adapted to move longitudinally upon the shaft, an interposed loose friction-disk and gearing connecting the disk with the main shaft, substantially as described. 45

4. The shaft *D*, wheel *d*, fixed thereon, disk *H*, loosely mounted on said shaft and carrying two wheels, *c c*, and the fixed flange *K*, provided with gear, in combination with a friction-surface adapted to be brought into contact with the disk, substantially as described. 55

5. The shaft *D*, having loosely mounted thereon a drum, *E*, and friction-disk *H*, a gear-wheel, *d*, fixed to the shaft and revolving therewith, in combination with two gear-wheels, *c c*, revolving upon axles secured in the loose disk *H*, and the stationary gear on the flange *K*, substantially as described. 60

6. The pedestal *M*, forming a bearing for one end of the shaft *D*, and provided with disk *L*, having flange *K*, supplied with gear-teeth on its inner surface, in combination with drum *E*, adapted to move longitudinally upon the shaft *D*, an interposed loose friction-disk, *H*, and gearing *c c* and *d*, connecting the disk *H* with the main shaft, substantially as described. 65 70

In testimony whereof I affix my signature in presence of two witnesses.

BENJAMIN W. GRIST.
